MEANS FOR MOUNTING ORNAMENTAL
WHEEL ACCESSORIES

George Albert Lyon, Allenhurst, N.J.

Application November 5, 1936, Serial No. 109,251

5 Claims. (CL 301—37)

This invention relates to means for mounting an ornamental member on a wheel and more particularly to means which require only a slight force to mount the ornamental member on the wheel but which require a relatively great force to disengage the ornamental member from the wheel.

In designing ornamental members adapted to be secured on the outer side of a wheel, it is considered important to provide a construction which may quickly and easily be assembled, which will not accidentally come off due to vibration or sudden jar, and which may readily be disassembled when desired. The most desirable construction, therefore, would include a mounting means which requires very little force to assemble the ornamental member on the wheel, but which requires a relatively great force to remove the ornamental member from the wheel. Furthermore, mounting means of the above type preferably should be hidden from view in the assembled position of the ornamental member on the wheel.

It is an object of this invention to provide a novel wheel assembly possessing the above highly desirable characteristics.

It is a further object of this invention to provide a novel wheel assembly including novel means for mounting an ornamental member on a wheel which is economical to manufacture and which is rugged and reliable in use.

It is a still further object of this invention to provide a novel means for mounting an ornamental wheel accessory on a wheel which requires only a relatively small force to mount the accessory but which requires a relatively great force to dismount the accessory from the wheel.

Another object of this invention is to provide a novel means for mounting a plurality of ornamental members on a wheel.

Another and further object of this invention is to provide novel means for mounting an ornamental member on a wheel, the means being secured to the inner face of the wheel and extending through apertures in the wheel to detachably engage the ornamental member.

Another and still further object of this invention is to provide means for mounting an ornamental member on a wheel including a plurality of leaf spring ornamental member retaining elements of a novel design which elements operate in a novel manner to detachably secure the ornamental member to the wheel.

The novel features which I believe to be char-

acteristic of my invention are set forth with particularity in the appended claims. My invention itself, however, both as to its organization and manner of construction, together with further objects and advantages thereof, may best be understood by reference to the following description taken in connection with the accompanying drawings, in which:

Figure 1 is an elevational view partly in cross section of the upper half of a wheel assembly including an ornamental member and the novel means for mounting the ornamental member on the wheel;

Figure 2 is a front elevational view of a wheel assembly, a portion of the ornamental member being broken away to show the means for mounting the ornamental member on the wheel;

Figure 3 is a fragmentary elevational view, partly in cross section, similar to the upper right hand portion of Figure 1 but showing a slightly modified form of ornamental member retaining means;

Figure 4 is a side elevational view, partly in cross section, of the upper half of a wheel assembly illustrating an ornamental member of different configuration from that shown in Figure 1 but having substantially the same form of ornamental member retaining means on the wheel;

Figure 5 is a fragmentary view, partly in cross section, illustrating a different embodiment of my invention;

Figure 6 is a fragmentary view, partly in cross section, illustrating a slightly modified form of the embodiment of my invention illustrated in Figure 1; and

Figure 7 is a view similar to Figure 6 but shows a novel arrangement whereby the trim ring is temporarily held in place during the assembling of the central ornamental member.

Referring now to Figures 1 and 2 of the drawings, the wheel assembly illustrated includes a wheel 10 having a rim part 11 and a body part 12. Rim 11 is illustrated as being of the usual drop center type having a base flange 13, opposite side flanges 14, opposite intermediate flanges 15, and opposite edge portions 16. Body part 12 is illustrated as having a configuration similar to that recently adopted by many manufacturers to permit the use of a brake drum 17 which extends well beneath the base flange 13 of rim 11. As will be seen from the drawings, body part 12 includes a substantially laterally extending flange 18, the outer edge portion 19 of which is adapted to fit below the base flange 13 of rim 11 and be secured thereto in any suitable manner, such

as by welding, riveting, or the like. The central portion of the body part 12 includes a circular holding flange 20 which is adapted to be secured by suitable bolts 21 (preferably five) to the axle plate 22 on the front face of brake drum 17.

5 Two ornamental members 23 and 24 are shown disposed on the outer side of wheel 10. Ornamental member 23 is a relatively large dome shape member having an undeturned outer edge 10 25. Ornamental member 24 is illustrated as having some suitable configuration which is pleasing to the eye and includes an unturned outer peripheral edge 26 which is adapted to bear against outer edge portion 16 of rim 11, and it is also 15 provided with an undeturned inner edge portion 27 which is adapted to extend into biting engagement with the outer intermediate flange 15 of rim 11. As is well known to those skilled in the art, the biting engagement made by undeturned edge 27 with a portion of rim 11 causes 20 ornamental member 24 to be tightly and substantially permanently mounted on the wheel.

The novel ornamental member retaining means, which forms one of the cardinal features 25 of the present invention will now be described. Secured to the outer face of body part 12 is a plurality of leaf spring elements formed of some suitable resilient material, such as spring steel. Elements 28 include a tail portion 29, an intermediate or main portion 30, and an end portion 31. Tail portion 29 is secured to the front face of body part 12 in any suitable manner, such as by a rivet 32. The intermediate portion 30 of element 35 28 extends radially outwardly and slightly rearwardly as is clearly indicated in the drawings. The outer end portion 31 of each leaf spring element 28 is bent so as to form a substantial angle with the main portion 30 of element 28 for a reason which will presently be described.

40 As may be seen in Figure 1 of the drawings, the free end portion 31 of the leaf spring element 28 extends into aperture 33 located in laterally extending flange portion 18 of body part 12 in close proximity to the base flange 13 of rim 11. 45 When spring elements 28 are in their normal unstressed position, the main body parts 30 or elements 28 lie away from laterally extending flange 18. That is, elements 28 are free to flex either toward or away from body part 12 of wheel 10. 50 As ornamental member 23 is moved into desired position on wheel 10, elements 28 are flexed radially inwardly towards flange 18 by reason of the camming action of undeturned edge 25 of member 23 on the main portion 30 of element 28. 55 This camming action continues until the high points 34 of elements 28 snap up into ornamental member retaining position behind undeturned edge 25.

It is to be observed that while elements 28 are 60 easily flexed by a relatively slight deformation force in response to axially inward movement of member 23, elements 28 are extremely difficult to flex in response to axially outward movement of member 23. As the undeturned edge 25 starts 65 to move axially outwardly, the only way in which elements 28 can flex to permit such movement is for the undeturned tip portion 31 of element 28 to slip rearwardly and radially inwardly. That is to say, outward movement of member 23 also 70 causes inward flexing of element 28, and the force required to effect the flexing is relatively great compared with that required for inward movement of member 23, for in this case the free ends of elements 28 must move in a direction against 75 the direction of the applied force. (It is, of

course, to be understood that the term "against" as used herein is not to be limited to mean a direction 180° and only 180° from the direction of the applied force, but on the other hand is used in its broader sense to mean "not having any 5 component in the same direction".)

From the above description, it will be apparent that I have provided an extremely simple yet effective arrangement for detachably securing an ornamental member to a wheel. The novel arrangement permits the ornamental member to be mounted on the wheel by simply moving it axially inwardly against the side of the wheel. It should also be noted that with this particular arrangement, the ornamental member will be self-centered on the wheel. It will also be observed that while only a very slight axial pressure on the outside of the ornamental member is necessary to snap it into retaining engagement with the springs carried on the wheel (in fact, it has been found in practice that an ornamental member of the character described may be mounted by simply pressing on it with one or two fingers), a relatively great force is necessary to dismount the ornamental member from the wheel. One 25 convenient method for dismounting the ornamental member from the wheel is to insert the relatively sharp edge of a pry-off tool between the outer marginal extremity of ornamental member 23 and the intermediate side flange 14 30 of rim 11 and then give the tool a sharp jerk.

In Figure 3 of the drawings, a slightly modified form of spring element is illustrated which requires a slightly greater force to remove the ornamental member than that required for the spring construction just described. In this modified form, the wheel construction and the form of ornamental members are identical to that of the preferred embodiment and therefore have been given the same reference numerals. The leaf 40 spring elements 28, however, have undeturned lips 35 at their extreme free ends which are adapted to engage the under surface 36 of flange 18. This construction permits elements 28 to be stressed in their normal position. That is to say, 45 the spring elements 28 may be stressed so that they tend to move outwardly but are restrained from such movement by lips 35. As will be apparent to those skilled in the art, this stressing of elements 28 in their normal position increases the 50 amount of the deformation force necessary to flex elements 28 both by the inward movement of member 23 and by the outward movement thereof. That is to say, since elements 28 flex inwardly not only during the mounting operation 55 but also during the dismounting of the ornamental member from the wheel, it is obvious that the stressing of elements 28 which tends to have them move outwardly increases the amount of force necessary to flex them inwardly. In this slightly modified arrangement of the preferred embodiment of my invention, the ornamental member is assembled and disassembled in precisely the same way as previously described in connection with Figures 1 and 2.

In Figure 4 of the drawings, spring elements similar to those described in the preferred embodiment of the invention are shown, but they cooperate with a different form of ornamental member. The configuration of the wheel nave or body part is also slightly different. Those elements of the wheel assembly which are similar to those previously described and illustrated will be given the same reference numerals, and no further description thereof will be made. Re-

ferring now to the drawings, a single ornamental member 37 has been substituted for the two ornamental members 23 and 24 shown in Figures 1 and 2. Ornamental member 37 includes a circle 5 dome portion 38, and an outer integral ring portion 39. An annular intermediate reentrant groove 40 is formed in member 37 for the dual purpose of providing a radially inwardly extending flange and of providing a suitable groove in 10 which a pry-off tool may be inserted to remove the ornamental member 37 from its mounted position on wheel 10. As will be observed from the drawing, the intermediate reentrant groove or flange 40 acts in the wheel assembly combination in substantially the same way and for the same purpose as the undeturned marginal edge 25 of the preferred embodiment does. Ornamental member 37 is mounted on and dismounted from wheel 10 in the same manner as ornamental 15 member 23 is mounted on the wheel illustrated in Figure 1.

In Figure 5 of the drawings, a different modification of this invention is shown. In this wheel assembly combination, the wheel rim and the ornamental members adapted for disposition on the outer side of the wheel are the same as described in Figure 1, but the wheel body parts and the leaf spring ornamental member retaining elements are slightly different. Those elements 20 which are substantially identical to corresponding elements in Figure 1 have been given the same reference numerals for purposes of clarity. In this arrangement the substantially laterally extending flange 18 of the wheel body part 12 is 25 provided with two series of apertures 33 and 41 respectively instead of the single series of apertures as previously described. In this arrangement the tail portions 29 of spring elements 28 extend down through the outer series of apertures 40 41 into engagement with the inner surface of wheel body part 12. Tail portions 29 of elements 28 are secured to the body part 12 of wheel 10 in any suitable manner, such as by means of rivets 32. The main body portions 30 of elements 28 45 extend radially outwardly and rearwardly, and the tips or end portions 31 of elements 28 extend rearwardly and radially inwardly through apertures 33. As will be readily understood, this disposition of the tail pieces 29 of elements 28 along 50 the inner surface of body part 12 renders the exterior appearance of the wheel more pleasing when the ornamental member 23 has been removed from the wheel. The various elements of the wheel assembly combination cooperate in substantially the same way in the mounting and dismounting of ornamental member 23 of this modification.

In Figure 6 of the drawings, an arrangement quite similar to the preferred embodiment of the 60 invention illustrated in Figure 1 of the drawings is shown. Those elements in Figure 6 which are identical with corresponding elements in Figure 1 have been given the same reference numerals for purposes of clarity. In this arrangement, however, the ornamental trim ring 42 is secured in place by means of the same spring elements 28 which secure the ornamental member 23 in place. Trim ring 42 may be given any configuration which is pleasing to the eye but preferably is 65 of the configuration indicated in the drawings. The outer marginal edge 43 of trim ring 42 is undeturned and adapted for disposition against the outer edge portion 16 of rim 11. The inner marginal edge 44 of trim ring 42 is outwardly turned and adapted to rest in intimate contact

with the curled outer edge 25 of ornamental member 23. From the drawings, it will readily be apparent that the spring pressure of elements 28 which retain ornamental member 23 in desired position on the wheel also retains ornamental trim ring 42 in desired position by reason of the fact that the outer turned inner marginal edge 44 of trim ring 42 lies between side flange 14 of rim 11 and the curled outer edge 25 of ornamental member 23. Ornamental member 23 retaining elements 28 function in the combination in precisely the same manner as that described in connection with the preferred embodiment of the invention illustrated in Figures 1 and 2 of the drawings. To assemble ornamental trim ring 42 10 in ornamental member 23 on wheel 10, the ornamental trim ring 42 is disposed in desired position against the outer side of rim 11, and the ornamental member 23 is snapped over elements 28 against the outer turned inner marginal edge 20 44 of ornamental trim ring 42. As ornamental member 23 is moved into desired position, elements 28 snap up behind under turned edge 25 into retaining engagement therewith. To dismount the ornamental members from the wheel, 25 a much greater force is necessary, and hence, the members may be conveniently removed by any suitable pry-off tool.

In Figure 7 of the drawings, an arrangement somewhat similar to that shown in Figure 6 is 30 illustrated, but in this instance provision is made for temporarily supporting the ornamental trim ring in desired position attending the assembly of the central ornamental member in position on the wheel. For purposes of clarity, those elements which are substantially the same as corresponding elements in Figure 6 have been given the same reference numerals. Referring now to the drawings, it will be noted that the outwardly bent inner marginal edge 44 of trim ring 42 is 35 provided with a reverse curve at its extreme end as at 45. The reverse curve portion 45 is adapted to engage the end portions 31 of leaf spring elements 28 prior to the time when the ornamental member 23 is moved into position on the wheel. 40 The cooperation of the spring elements 28 with the reverse curve portion 45 of trim ring 42 at a time prior to the assembling of ornamental member 23 on wheel 10 is clearly indicated by the dotted line in the drawings. As ornamental member 23 is moved into desired position on wheel 10, the curled outer edge 25 rides over the spring element 28 as previously described and nests against the curved portion 44 of trim ring 42. It 45 will be noted that when ornamental member 23 is in this position, the reverse curved portion 45 of trim ring 42 does not rest in contact with the end portion 31 of element 28, this being necessary in order to insure the application of the spring pressure through the curved portion 25 and then 50 through curved portion 44 of trim ring 42 to side flange 14 of rim 11.

From the above description, it will be seen that I have provided an extraordinarily simple and yet effective means for mounting ornamental members on wheels. The novel means includes the highly desirable characteristic which requires only a slight deformation force to assemble the ornamental member or members on the wheel but which requires a relatively great force to dismount 70 the member or members from the wheel.

While I have shown particular embodiments of my invention, it will of course be understood that I do not wish to be limited thereto, since many modifications may be made, and I, therefore, con- 75

template by the appended claims to cover all such modifications as fall within the true spirit and scope of my invention.

I claim as my invention:

- 5 1. The combination comprising a wheel having an intermediate annular series of apertures, an ornamental member for disposition on the outer side of said wheel, said member having a radially inwardly extending annular flange portion, and a plurality of leaf spring ornamental member retaining elements each secured at one end to the inner side of said wheel and extending radially outwardly through said apertures leaving free end portions on the exterior side of said wheel, said 10 free end portions being shaped to extend obliquely radially outwardly and axially rearwardly and terminating in an obliquely radially inwardly bent tip which engages said flange at a point axially rearwardly of the plane of attachment of said elements to said wheel, thereby to detachably retain said ornamental member on said wheel.
- 15 2. The combination comprising a wheel having an intermediate annular series of apertures, an ornamental member for disposition on the outer side of said wheel, said member having a radially inwardly extending annular flange portion, and a plurality of leaf spring ornamental member retaining elements each secured at one end to the inner side of said wheel and extending radially outwardly through said apertures leaving free end portions on the exterior side of said wheel, said 20 free end portions being shaped to extend obliquely radially outwardly and axially rearwardly and terminating in a tip portion which is bent to form 25 a flange engaging surface which lies substantially on the surface of an imaginary cone whose apex is axially inwardly of the plane of the wheel.
- 30 3. The combination comprising a wheel, an ornamental member for disposition on the outer side of said wheel having an undeturned marginal edge, and a plurality of resilient leaf ornamental member retaining elements each secured to said wheel on the inboard side thereof, said wheel having an annular series of apertures there- 35 in through which said retaining elements extend 40
- 45

in a substantially radial direction, each of said retaining elements being shaped and disposed to extend obliquely axially inwardly and radially outwardly of their point of attachment to the wheel, and each element being bent at its free end 5 to form a cam surface at a substantial angle to the direction of normal extension, said cam surface being adapted to engage said undeturned edge to retain said ornamental member in desired position on said wheel.

4. The combination comprising a wheel, an ornamental member for disposition on the outer side of said wheel, and a plurality of resilient attaching elements each secured at one end to the inboard side of said wheel, said wheel having an annular series of apertures through which said 15 spring elements extend to the outboard side of said wheel, the portion of each of said elements lying on the outboard side of said wheel being bent obliquely axially rearwardly and radially outwardly and terminating in a bent tip portion extending obliquely axially rearwardly and radially inwardly, said bent tip portion being disposed to engage 20 said ornamental member and retain said member in desired position on said wheel.

5. The combination comprising a wheel, an ornamental member for disposition on the outer side of said wheel, and a plurality of resilient attaching elements each secured at one end to the inboard side of said wheel, said wheel having an annular series of apertures through which said 30 spring elements extend to the outboard side of said wheel, the portion of each of said elements lying on the outboard side of said wheel being bent obliquely axially rearwardly and radially outwardly and terminating in a bent tip portion extending obliquely axially rearwardly and radially inwardly, said bent tip portion being disposed to engage 35 said ornamental member and retain said member in desired position on said wheel, said wheel having a second annular series of apertures opposite the end of said bent tip portion of said spring element into which said bent tip portion extends.

GEORGE ALBERT LYON. 45
